US00D882230S

(12) United States Design Patent (10) Patent No.: US D882,230 S
(45) Date of Patent: * Apr. 28, 2020

(54) SHOE

- (71) Applicant: NIKE, Inc., Beaverton, OR (US)
(72) Inventor: Morgan Stauffer, Portland, OR (US)
(73) Assignee: NIKE, Inc., Beaverton, OR (US)
() Term: 15 Years
(21) Appl. No.: 29/670,579
(22) Filed: Nov. 16, 2018

Related U.S. Application Data

- (63) Continuation of application No. 29/604,159, filed on May 15, 2017, now Pat. No. Des. 839,570.

L.L.P.(57) CLAIM

The ornamental design for a shoe, as shown and described.

DESCRIPTION

The FIGURE is a bottom view of a shoe showing my design. The even-length broken lines are directed to environment, represent unclaimed subject matter, and form no part of the claimed design.

1 Claim, 1 Drawing Sheet(56)
